(57) **CLAIM**

What is claimed is the ornamental design for a “vise with anvil”, as shown and described.

DESCRIPTION

FIG. 1 is a front perspective view of the “vise with anvil” of Applicant’s invention.

FIG. 2 is a back perspective view of the “vise with anvil” of Applicant’s invention.

FIG. 3 is a front side elevation view of the “vise with anvil” of Applicant’s invention.

FIG. 4 is a rear side elevation view of the “vise with anvil” of Applicant’s invention.

FIG. 5 is a left side elevation view of the “vise with anvil” of Applicant’s invention, which is a mirror of a right side elevation view of the “vise with anvil”.

FIG. 6 is a top view of the “vise with anvil” of Applicant’s invention; and,

FIG. 7 is a bottom view of the “vise with anvil” of Applicant’s invention.

The broken lines in the figures illustrate portions of applicant’s “vise with anvil” that form no part of the claimed design.
